COLONIC IRRIGATOR

Dan L. F. Coombs, Kansas City, Mo.

Application June 17, 1941, Serial No. 398,490

6 Claims. (Cl. 128—227)

This invention relates to irrigators and more particularly to irrigators employed for treating the anatomical colons, for example, of human beings; the principal object of the invention being to provide a convenient, relatively economical and highly efficient irrigator of the character noted.

Other objects of the invention are to provide for applying a controlled supply of a fluid and/or a liquid and gas mixture, of which water and air are examples, to a colon for treating the same; to provide for controlling the mixture of said liquid and gas; to provide for massaging the colon; to provide for locating the point of massage in relation to parts of the irrigator exteriorly of the colon; to provide for maintaining a substantially constant pressure of treating fluid on and in the colon being treated; to prevent pollution of supplies of treating fluids; to prevent detrimental siphoning effects in the irrigator; to provide for entrapping gas normally entrained in the treating liquid for maintaining a properly mixed fluid for treating the colon; and to provide improved elements and arrangements thereof in an irrigator of the character and for the purposes set forth.

In accomplishing these and other objects of the present invention, I have provided improved details of structure, the preferred form of which is illustrated in the accompanying drawings, wherein:

Fig. 1 is a perspective view of an irrigator embodying the features of the present invention.

Fig. 2 is a diagrammatic view of a colon showing the manner of treating the same with my improved irrigator.

Fig. 3 is a front elevational view of the preferred piping arrangement of my improved irrigator, the cover housing therefor being broken away.

Fig. 4 is a vertical sectional view of a check valve and vacuum break forming a part of the present invention.

Fig. 5 is a vertical cross-sectional view of an aspirator and a needle valve therefor, forming part of the present invention.

Referring more in detail to the drawings: I generally designate an irrigator embodying the features of the present invention, which preferably includes hot and cold water lines 2 and 3 leading from a suitable source of supply, such as city water mains, not shown. The lines 2 and 3 are preferably valved, as at 4 and 5 and communicate with a mixing chamber 6, that is controlled by an adjustable thermostatic valve 7, through connections 8 and 9. Surge

pipes 10 and 11 are preferably provided above the mixing chamber connections to form air cushions in the water lines and prevent hammering during flow.

From the thermostatically valved mixing chamber 6, a line 12 extends upwardly to a suitable height, a preferably gas pressure sensitive thermometer 13 being interposed in the line 12 to indicate the temperature of the tempered flow from the chamber 6.

A valve 14 controls flow through the line 12 from the mixing chamber 6, from which valve 14 a pipe connection 15 extends further upwardly into a combination back pressure check valve and vacuum breaking element 16, Fig. 4.

The element 16 preferably includes a housing having an inlet 17, in which the connection 15 is suitably engaged, leading past a valve seat 18 to a lateral outlet 19. A valve 20 normally engages the seat 18, and lifts under fluid pressure to open the inlet 17 to the outlet 19 and close the air port 21 above the valve seat. The port 21 normally communicates the outlet 19 with an air chamber 22 in the housing of the element 16, which is supplied with air under atmospheric pressure through ducts 23 between the upper edge of the element housing and a hood 24 therefor.

A pipe connection 25 preferably leads horizontally from the laterally arranged outlet 19 to the inlet 26 of an aspirator needle valve housing 27 that is provided with a head 28 having a threaded passage for receiving the threaded shank of a needle valve 29, this valve being vertically adjustable relative to a cap on the head 28 by a suitable tool. Adjustment of the needle valve seats and/or unseats the same relative to a seat 30 in a downwardly directed outlet 31 from the aspirator valve housing 27, the outlet being provided with a further downwardly extending tube 32 that passes through a chamber 33 in the aspirator housing 34 and into the upper end of a pipe connection 35.

It is desirable to add a gas, preferably air, to the liquid, which liquid in this instance is preferably water. To this end, the aspirator housing chamber 33 is supplied with air by a line 36 that preferably extends laterally of said chamber and communicates with the lateral connection 37 of a valve 38 for controlling admission of air to the line 36 and aspirator housing. The lower opening of the valve 38 communicates with a T 39. The lateral opening of the T 39 is provided with an air inlet duct 40 that extends upwardly approximately to the height of the check valve and vacuum break.

Gas having been applied to the liquid, the mixture thereof, caused by entrainment, flows downwardly through the pipe connection 35 to a sight tube 41 by which the proper mixture of gas and liquid may be determined as by a characteristic spiral movement of the mixture. The sight tube may be provided with a suitable evacuator, such as the pet-cock 42 illustrated.

From the sight tube 41, the flow continues downwardly through a pipe connection 43 to a discharge outlet 44 that is preferably controlled by a valve 45.

It has been found desirable, in maintaining a proper gas and liquid mixture in the flow, to provide a trap 46, preferably formed by a downwardly and then upwardly turned continuation of the pipe connection 43, the latter then extending upwardly, as at 47, to establish a column of fluid constituting a substantially constant hydrostatic head of pressure on the flow at the discharge outlet 44 for the flow and being provided with a fitting 48 at its upper end leading to an overflow pipe 49. It has been found that a suitable distance between the fitting 48 and discharge 44 is approximately forty-two (42) inches. The overflow pipe preferably communicates at its upper end with a pipe connection 50 leading to the lower opening of the T 39, thence to atmosphere through the duct 40, the pressure of the atmosphere preventing siphoning action that might normally be caused by overflow.

The overflow pipe 49 leads downwardly to a sewer discharge outlet 51 and is then preferably provided with an upwardly extending continuation 52 to serve as a precautionary overflow pipe should the sewer become stopped from any cause and thus obviating the danger of excess back pressures against the proper flow of mixed fluid.

With the construction thus far described, it is apparent that a flow of air and water may be and is controlled in such a manner that the temperature, pressure, back-flow, mixture, stabilization of such mixture, and a suitable static pressure thereon are regulatable to produce a particular set of conditions affecting the flow at said discharge outlet 44. For example, with a flow of approximately nine (9) pints of water per minute, with sufficient air entrained therein to cause the flow to spiral, as seen in the sight tube, and with a hydrostatic head of pressure on the flow of about three (3) ounces, preferably as a maximum, the flow is in a condition suitable for application, preferably by a trained attendant, to the colon of a patient undergoing treatment.

In order to properly apply such flow, a preferably flexible tube 53 is applied to the flow discharge outlet 44, which tube leads to a preferably curved inlet connection 54 to a central passage 55 of an obturator 56, the outer nozzle end 57 of which is applicable to the opening 58 at the outlet of the colon 59 and the inner end of which is connected, as at 60, with an end of a flexible tube 61, preferably of greater inner diameter than the inner diameter of the tube 53; where, for example, the distance is forty-two (42) inches between the discharge 44 and fitting 48, a satisfactory and the preferable length of the tube 61 is also forty-two (42) inches.

The end of the flexible tube 61, remote from the obturator, is preferably provided with a valve 62 that may be and preferably is, supported by a stand 63 having a bracket 64 thereon, which in turn supports a sight tube 65 by which the flow and contents thereof may be examined to aid in determining the pathological condition of 75

the patient. From the sight tube 65, the flow passes through another preferably flexible tube 66 into the sewer discharge outlet 51.

67 designates a table or the like for supporting a patient in proper position in relation to the flow discharge outlet 44 and hydrostatic head of pressure thereon. This relation preferably is a slightly higher plane for the table than the discharge outlet. For example, if the discharge outlet is twenty-six (26) inches above the floor supporting the table 67, a satisfactory height for the table is approximately twenty-eight (28) inches.

68 designates a suitable cabinet to house the pipe fittings and certain of the valves, which cabinet may be and preferably is, mounted on a backboard 69 of suitable character which latter may be suitably mounted for support on a wall or the like in a clinic, for example, in which this apparatus is especially designed to be located.

The operation of an apparatus constructed as described, is as follows:

Hot and cold water are admitted in controlled quantities to the mixing chamber and rise in a column under valved control to the check valve and vacuum break, thence laterally past the needle valve and then downwardly to entrain controlled quantities of air therein.

As the mixed water and air flow passes through the sight tube 41 its character may be determined and controlled in accordance with requirements.

Continued downward flow of the fluid, assuming the discharge outlet valve 45 to be closed, carries the flow beyond such discharge through the trap 46, then upwardly into a hydrostatic head pressure forming column and finally to the overflow pipe and to the sewer; siphoning action meanwhile being obviated by atmospheric pressure acting through the air ducts 40 and 50.

When the valve 45 is opened, the flow substantially in its entirety, passes through the tube 53 to the nozzle opening of the obturator and/or the flexible tube 61. When the obturator nozzle is stopped, and with the valve 62 open, the flow is through the tube 61, sight tube 65 and tube 66 to the sewer discharge outlet 51.

When the valve 45 is opened, the valve 62 closed and the obturator applied to the colon, as shown in Fig. 2, the flow is to the colon substantially filling the same with an air and water mixture. The valve 45 is then closed to establish a closed circuit of properly mixed fluid under proper pressure.

It is then preferable for an attendant to manually, intermittently and rhythmically squeeze the flexible tube 61 to cause a disturbance in the fluid mixture, due to the compressibility of the air in the mixture and thus cause a massaging effect to be applied to the interior of the colon.

An extraordinary phenomenon has been discovered in connection with the operation just above described. While the actual lengths of the colon being treated and the tube 61 may vary considerably, those lengths are related in that constricting pressure at any portion throughout the length of the tube 61 causes a corresponding reaction at the portion of the colon proportional in distance from the obturator, to the distance from the obturator of the constricted portion of the tube. Thus when the tube 61 is manually squeezed at the point A, as indicated in Fig. 2, which may be at a point representing approxi-

mately two-thirds (2/3) of the length of the tube, the colon is acted upon at a point B approximately two-thirds (2/3) up the total length of the colon.

After the colon has been massaged and, in effect, scoured, the valve 62 is opened and the flow passed through the sight tube 65 for examination. The flow then passes through the tube 66 to the sewer for discharge and suitable disposition.

It is apparent, therefore, that I have provided a convenient, relatively economical, efficient, safe and sanitary colonic irrigator that is admirably suited for the purposes for which it was designed.

What I claim and desire to secure by Letters Patent is:

1. In an apparatus of the character described, a mixing chamber, means for supplying hot and cold water to said mixing chamber, means for elevating the water from the mixing chamber in a column, a combination check valve and vacuum break substantially at the upper end of said column, means for conveying the water laterally of said combination valve and break, a valve housing for receiving said laterally conveyed water having a needle valve and an aspirator associated therewith, means for supplying the aspirator with air for entrainment in said water, means leading the water with air entrained therein downwardly, a discharge outlet at the lower end of said last named water leading means.

2. In an apparatus of the character described, a mixing chamber, means for supplying hot and cold water to said mixing chamber, means for elevating the water from the mixing chamber in a column, a combination check valve and vacuum break substantially at the upper end of said column, means for conveying the water laterally of said combination valve and break, a valve housing for receiving said laterally conveyed water having a needle valve and an aspirator associated therewith, means for supplying the aspirator with air for entrainment in said water, means leading the water with air entrained therein downwardly, a discharge outlet at the lower end of said last named water leading means and an extension on said last named water leading means having a trap therein for causing air to be retained in the water.

3. In an apparatus of the character described, a mixing chamber, means for applying hot and cold water to said mixing chamber, means for elevating the water from the mixing chamber in a column, a combination check valve and vacuum break substantially at the upper end of said column, means for conveying the water laterally of said combination valve and break, a valve housing for receiving said laterally conveyed water having a needle valve and an aspirator associated therewith, means for supplying the aspirator with air for entrainment in said water, means leading the water with air entrained downwardly, a discharge outlet at the lower end of said last named water leading means, and an extension on said last named water leading means having a trap therein for causing air to be retained in the water, said extension being directed upwardly to form a column of water and air for establishing a predetermined hydrostatic head of pressure on said air and water at said discharge outlet.

4. In an apparatus of the character described, a mixing chamber, means for supplying hot and cold water to said mixing chamber, means for elevating the water from the mixing chamber in

a column, a combination check valve and vacuum break substantially at the upper end of said column, means for conveying the water laterally of said combination valve and break, a valve housing for receiving said laterally conveyed water having a needle valve and an aspirator associated therewith, means for supplying the aspirator with air for entrainment in said water, means leading the water with air entrained therein downwardly, a discharge outlet at the lower end of said last named water leading means, an extension on said last named water leading means having a trap therein for causing air to be retained in the water, said extension being directed upwardly to form a column of water and air for establishing a predetermined hydrostatic head of pressure on said air and water at said discharge outlet, a downwardly directed connection at the upper end of said extension forming an overflow connection, and a sewer discharge outlet connected with said overflow connection.

5. In an apparatus of the character described, a mixing chamber, means for supplying hot and cold water to said mixing chamber, means for elevating the water from the mixing chamber in a column, a combination check valve and vacuum break substantially at the upper end of said column, means for conveying the water laterally of said combination valve and break, a valve housing for receiving said laterally conveyed water having a needle valve and an aspirator associated therewith, means for supplying the aspirator with air for entrainment in said water, means leading the water with air entrained therein downwardly, a discharge outlet at the lower end of said last named water leading means, an extension on said last named water leading means having a trap therein for causing air to be retained in the water, said extension being directed upwardly to form a column of water and air for establishing a predetermined hydrostatic head of pressure on said air and water at said discharge outlet, a downwardly directed connection at the upper end of said extension forming an overflow connection, and a sewer discharge outlet connected with said overflow connection.

6. In an apparatus of the character described, a mixing chamber, means for supplying hot and cold water to said mixing chamber, means for elevating the water from the mixing chamber in a column, a combination check valve and vacuum break substantially at the upper end of said column, means for conveying the water laterally of said combination valve and break, a valve housing for receiving said laterally conveyed water having a needle valve and an aspirator associated therewith, means for supplying the aspirator with air for entrainment in said water, means leading the water with air entrained therein downwardly, a discharge outlet at the lower end of said last named water leading means, an extension on said last named water leading means having a trap therein for causing air to be retained in the water, said extension being directed upwardly to form a column of water and air for establishing a predetermined hydrostatic head of pressure on said air and water at said discharge outlet, a downwardly directed connection at the upper end of said extension forming an overflow connection, and a sewer discharge outlet connected with said overflow connection.

nection, an extension on said overflow connection directed upwardly relative to said sewer discharge outlet forming an auxiliary discharge outlet or said overflow connection, a tube leading from said discharge outlet, an obturator having an inlet connected with said tube and having a

5 nozzle and an outlet, a flexible tube connected with the outlet of said obturator, a valve for said flexible tube, a sight tube connected with said flexible tube, and a tube connected with said 5 sight tube leading to said sewer discharge outlet.

DAN L. F. COOMBS.
